7 Claims. (Cl. 179—171)

In order to modulate high frequency transmitters methods are known in which a saving of energy is effected by separating carrier frequency and side bands from each other, these two then being amplified and sent out separately. Such methods have the disadvantage that the carrier amplifier may operate at a high efficiency, only the side band amplifier having to operate at a low efficiency. In arrangements of this kind, however, it is not possible to cause the two amplifiers to act on an antenna common to them, because due to a reaction of impedance variations that occur in the antenna the highly efficient carrier amplifier will deliver less power if the modulation degree is increasing. If such decrease in power output were to be avoided then the carrier amplifier would have to operate at lower efficiency, whereby however the desired saving of energy would get lost. Therefore, as stated before, the two amplifiers have been caused to act on separate antennae which are as far as possible neutralized with regard to each other, so that there shall be no coupling effect between them. To such end the antennae are spaced apart by a sufficiently large distance, or additional means are provided for establishing an opposing coupling effect. Thus the impedance variations of that antenna on which the side band amplifier is acting are prevented from acting upon the output circuit of the carrier amplifier. This, however, has the disadvantage that a double antenna plant is used, thus involving great first cost and considerable space requirements.

The invention proposes to cause carrier amplifier and side band amplifier to act on a common or single utilization circuit and also provides means adapted to avoid the said reaction, that is, the influence which the side band amplifier has upon the carrier amplifier. These means reside in a reversal of the impedance variations that occur in the said common utilization circuit and in the final stage of the carrier amplifier, that is to say, if the impedance of the utilization circuit is increasing then the impedance of the output circuit of the carrier amplifier is decreased. This is effected by interposing between the utilization circuit and the output side of the carrier amplifier a member of the length $\lambda/4$, this member being capable of effecting such impedance reversal. λ denotes the wavelength.

From the following description the state of the art and the idea of the invention will be understood, reference being had to the accompanying drawings in which

Fig. 1 is a diagrammatic view of a known transmitting system having separate carrier- and side band amplifiers. Fig. 2 is a view similar to Fig. 1 and illustrates the fundamental idea of the invention. Fig. 3 is a graphic representation that serves to explain this idea. Fig. 4 is a wiring diagram of a device that forms part of the arrangements shown in Figs. 1 and 2 and acts to separate the side bands from the carrier. Fig. 5 is a graphic representation which serves to explain the function of amplifiers included in the arrangement shown in Fig. 2. Fig. 6 is a graphic representation that relates to the function of an amplifier adapted for use in connection with the arrangement shown in Fig. 2. Fig. 7 is a graphic representation which serves to explain distortions which occur in amplifiers of this kind. Fig. 8 is a graphic representation that relates to the function of amplifiers used in arrangements as provided by the invention. Fig. 9 is a wiring diagram of these arrangements.

Reverting to Fig. 1, in which a known arrangement is shown, S denotes the control stage, I the stage in which the side bands are separated from the carrier, the carrier being suppressed here. II designates the side band amplifier, E¹ the final stage of the side band amplifier, A¹ the antenna which emits the side band or the side bands. The modulation is effected by the modulation amplifier M connected in advance of stage I. The carrier is derived from stage S, is then amplified in the carrier amplifier III and is then conveyed over the final stage E² to antenna A².

In Fig. 2, which illustrates the inventive idea, the reference characters are as far as possible the same as used in Fig. 1. The two final amplifiers E¹, E² are here arranged to act on an antenna common to them. In the lead from E² to antenna A a member C¹ is interposed that acts to rotate the phase of the carrier by 90°. This phase rotation or phase shift, whenever the impedance of the antenna circuit increases under the action of the final stage of the side band amplifier E¹, causes the impedance at the output side of E² to decrease, and vice versa. If the output impedance of E² decreases then the power output of this stage will increase, since the operation takes place at high efficiency. In order, however, to ensure phase correctness of the carrier when supplied to the antenna the phase rotation effected in C¹ must be compensated. This is done in accordance with a feature of the invention by inserting a member C² before the final stage, this member acting to rotate the phase by 90° in the opposite direction. It is immaterial

where member C2 is interposed. For instance, it may be located in front of amplifier III or may be disposed between stages of this amplifier. The same result is obtained also if the phase rotation 5 by C2 is effected in the line in which the side band amplifier E1 is included, such rotation being caused here at a point in advance of E1. C2 may for instance be arranged in bridge connection. The loss due to such an arrangement is easily 10 compensated by amplifier III. In this case of course C2 would have to be interposed between S and III. Furthermore, C2 may be constituted by a chain system of any construction. C1 may of course be of the same construction as described 15 with regard to C2. As, however, the output at C1 is very great it will be convenient not to construct C1 as a phase bridge or chain system but to interpose an energy line, such for example as a concentric high frequency cable, of such length 20 that the phase rotation by 90° or so called phase quadrature shall be obtained in this way. Such cable may for instance be wound on a drum or may be bent on its way to the antenna coupling cabin. The first arrangement has the advantage 25 that only a single energy line leading from the transmitter to the antenna is necessary.

Fig. 3 shows how the output delivery of the final stage E2 increases with decreasing output impedance. The output efficiency N is here plotted with respect to the output impedance Z. The top of the curve is the limit between the high and low efficiency states. On the left-hand side of the dotted line g the operation is effected at 30 low efficiency while on the right-hand side thereof it takes place at high efficiency. Since, as stated, the carrier amplifier is to operate at a high efficiency, the working point is located in the region of high efficiency, for instance at P. To this working point a certain output efficiency N1 corresponds, the output impedance being of the 35 value Z1. By diminishing Z1, for instance to Z2, the efficiency increases to N2 while the working point is displaced from P to P'. This surplus efficiency with decreasing impedance is well known per se. However, no means have been proposed so far to convert an increase of the 40 impedance of the antenna circuit into a decrease of the output impedance of the amplifier. In accordance with the invention such means is constituted by the member C1. The construction of 45 the prestages II, III of the side band amplifier or carrier amplifier, respectively, is not of interest here. Stage I in which the side bands are separated from the carrier may be for instance in 50 push-pull connection in a well known manner. To the input side of this push-pull stage the modulating voltage is supplied in phase opposition while the carrier is supplied thereto in co-phasal relation. In the case of no modulation the 55 arrangement is balanced, that is to say, in the anode circuit of the push-pull stage the carrier currents will annul each other. If modulated, however, the balance is relieved in accordance with the 60 modulating voltages, and it is so in such manner that differential high frequency currents will flow in the anode circuit of the push-pull stage which correspond with the modulating voltages impressed upon the grids thereof. The fundamental 65 arrangement of such a push-pull stage is shown 70 in Fig. 4.

In the arrangement represented in Fig. 4 the modulating voltage is supplied over terminals 1, 2 while over terminals 3, 4 the carrier is supplied. At the output terminals 5, 6 only the side bands 75 are derived.

The same result is obtainable by means of an arrangement that acts to filter the carrier selectively, for instance with the aid of an oscillatory crystal.

In Fig. 5 the modulated carrier a is shown as 5 subjected to a modulation degree of 100%. By separating side bands and carrier from each other the curves b, c of Fig. 5 are obtained, b representing the carrier and c the side bands. The carrier b, Fig. 5, is still further amplified in the 10 carrier amplifier III, Fig. 2, while the side bands c are so in the side band amplifier II.

In order to save energy the final stage of the side band amplifier, i. e., the stage operating in a state of low tension, may be constructed as an 15 amplifier in Class B connection. Fig. 6 discloses the conditions which relate to such a Class B amplifier. The working point P is located in the lower bend of the idealized characteristic curve K. The side bands S' are conducted to the grid 20 of the stage and are after amplification derived from the anode circuit in an undistorted condition. With arrangements of this kind the at-rest current in its unmodulated state is equal to zero. However, the real characteristic curve of an 25 amplifier tube has no sharp bend at its lower end, that is to say, does not join the zero line in the manner represented in Fig. 6 but joins this by a curvature, as shown in Fig. 7. As a result, behind the final stage distortions arise, which depend upon the shape of the curvature. Fig. 7 shows how such distortions originate. If the 30 working point is made to be point P of the real characteristic K then in consequence of the curvature no undistorted curves are obtained at the 35 output side of the amplifier, but the resultant curves are flattened as illustrated at a. If the 40 working point is made to be point P', that is, the point where the characteristic ceases to be straight, then in the first place an at-rest current J is produced. That part of the side bands which 45 was to be suppressed is likewise amplified and therefore in its turn entails a distortion. The curves belonging to working point P' are designated b.

In order to avoid these non-linear distortions a further feature of the invention proposes to insert a single-way rectifier into the grid circuit of the Class B amplifier, such for example as a diode that acts to cut away one half of the side 50 bands. In this case the working characteristic of the rectifier should be made as straight as possible. Fig. 8 shows the mode of action of such an arrangement. The working point is point P, located at the end of the straight portion of the 55 characteristic K. Owing to the rectification effected by the diode, only curve lines of the kind represented in Fig. 8 are conveyed to the grid circuit of the tube, the other curve lines, which are in the nature of mirror reflections to the former, being cut away. Since point P is not located in the zero line, again an at-rest current J results which, however, is not troublesome as 60 stated before, being small as compared with the total current. From the anode circuit of the 65 amplifier a true or distortionless reproduction of the curves supplied to the arrangement may now be derived after amplification.

Fig. 9 by way of example shows a wiring diagram of the final stage of the Class B amplifier. 70 The working point P is adjusted by regulating the grid bias G. The diode D in the grid circuit acts to cut away one half of the curves conveyed over transformer T. By tuning the anode circuit of the stage the carrier wave may be filtered 75

out so that the two side bands are reproduced in their original form.

In accordance with still another feature of the invention the working point is displaced in the customary manner into the point where the characteristic curve of the Class B amplifier and the zero line intersect, and the working characteristic of the rectifier is so chosen that distortions which are due to the curvature of the amplifier characteristic shall be compensated by the curvature of the rectifier characteristic.

The novel arrangement thus ensures that when the carrier amplifier is operating at high efficiency an impedance increase that occurs in the utilization circuit does not decrease the power output but acts to increase it. In this way a saving in the expense for place requirements and installation is made as compared with prior arrangements of the kind operating likewise at high efficiency, since one of the usual antenna arrangements is now dispensed with. A surplus expenditure resides only in the provision of an additional length of energy line, namely the $\lambda/4$ length necessary for effecting the described 90° phase shift, this expenditure however being immaterial over the said advantage of the novel arrangement.

Owing to the invention it is possible to cause carrier amplifier and side band amplifier to act on a common or single utilization circuit. Therefore, in accordance with a feature of the invention the method of separate amplification may now be used in connection with radio transmission systems of the kind operating with conductors. For the reasons stated before this cannot be achieved with the means that have been provided in prior systems.

What is claimed is:

1. In a radio transmitting system having means for obtaining and separating side bands from a carrier, an amplifier for the carrier frequency, a high efficiency amplifier for the side bands, and a single utilization circuit, means for coupling said amplifiers to said utilization circuit

circuit, and means for reversing in the output circuit of the carrier amplifier impedance-variations occurring in said utilization circuit.

2. An arrangement defined in claim 1, wherein the side band amplifier is of the Class B type having a vacuum tube with anode, cathode and grid circuit, comprising a one-way rectifier included in the grid circuit and means adapted for displacing the working point into the starting point of the straight part of the characteristic curve of the Class B amplifier. 5

3. An arrangement defined in claim 1, wherein the side band amplifier is of the Class B type having a vacuum tube with anode, cathode and grid circuit, comprising a one-way rectifier included in the grid circuit and having a straight characteristic curve. 15

4. In an arrangement defined in claim 1, wherein the side band amplifier is of the Class B type having a vacuum tube with anode, cathode and grid circuit, comprising a one-way rectifier included in the grid circuit and means adapted for displacing the working point into the point of intersection of the characteristic curve and zero line, the characteristic curve of this rectifier being such that distortions caused by the characteristic curve of the Class B amplifier are compensated. 20 25

5. An arrangement according to claim 1, means inserted between the utilization circuit and the output circuit of the carrier frequency amplifier for quadrature phase shifting the high frequency output of said amplifier, and a second means producing the same angular phase shift to compensate for the first mentioned phase shift. 30 35

6. An arrangement according to claim 1, means inserted between the output of the carrier amplifier and said utilization circuit for shifting the phase of the carrier, said means comprising a transmission line of one-quarter wave length. 40

7. An arrangement according to claim 1, wherein the side band amplifier is of the Class B type.

ERICH SCHULZE-HERRINGEN.
